(57) **CLAIM**

The ornamental design for a beverage mixer and heater, as shown and described.

DESCRIPTION

FIG. 1 is an elevated, perspective view of the beverage mixer and heater in accordance with my invention;
FIG. 2 is a left side elevation view thereof;
FIG. 3 is a right side elevation view thereof;
FIG. 4 is a front elevation view thereof;
FIG. 5 is a back elevation view thereof;
FIG. 6 is a top plan view thereof; and,
FIG. 7 is a bottom plan view thereof.
The broken lines shown in FIGS. 1-7 are for illustrative purposes only and form no part of the claimed design.
